(57) **CLAIM**

The ornamental design for lighting apparatus, as shown and described.

DESCRIPTION

FIG. 1 is a perspective view of lighting apparatus showing my new design;

FIG. 2 is another perspective view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a front elevational view thereof; and,

FIG. 8 is a rear elevational view thereof.

The tubular element of the design, including the end caps, is transparent and discloses unclaimed portions of the article within, shown in broken lines.

The broken lines shown in the figures depict portions of the lighting apparatus in which the design is embodied that form no part of the claimed design.
